CLAIM

We claim the ornamental design for an electronic device battery, as shown and described.

DESCRIPTION

FIG. 1 is a front perspective view of an electronic device battery;

FIG. 2 is a back bottom perspective view of the electronic device battery;

FIG. 3 is a top plan view thereof;

FIG. 4 is a bottom plan view thereof;

FIG. 5 is a back elevational view thereof;

FIG. 6 is a front elevational view thereof;

FIG. 7 is a left elevational view thereof; and,

FIG. 8 is a right elevational view thereof.
